DESIGN FOR A BOTTLE

Joseph Goldblatt, Chicago, Ill., assignor to Lionel Distilled Products, Inc., Chicago, Ill., a corporation of Illinois

Application August 31, 1934, Serial No. 53,124

Term of patent 14 years

To all whom it may concern:

Be it known that I, JOSEPH GOLDBLATT, a citizen of the United States, residing at Chicago, in the county of Cook, State of Illinois, have invented a new, original, and ornamental Design for a Bottle,
of which the following is a specification, reference being had to the accompanying drawing, forming a part thereof, in which:

Figure 1 of the drawing is a front elevation;

at line 2 of Fig. 1.

I claim:

The ornamental design for a bottle as shown.
